Primary Examiner — Karen E Kearney*Assistant Examiner* — Carissa C Fitts(74) *Attorney, Agent, or Firm* — Caeden Drayton; Adan Ayala(57) **CLAIM**

The ornamental design for a workshop lamp, as shown and described.

DESCRIPTION

FIG. 1 is a perspective view of a new design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The broken lines show portions of the workshop lamp which form no part of the claimed design.
